Des. 208,613
Patented Sept. 12, 1967

208,613

PIPE CLEANING IMPLEMENT

Leo Schwartz, 111 E. 56th St., New York, N.Y. 10022

Filed Aug. 12, 1966, Ser. No. 3,453

Term of patent 14 years

(Cl. D85—7)

FIG. 1

FIG. 2

FIG. 3

FIG. 4

FIG. 5

FIG. 1 is a side elevational view of a pipe cleaning implement, showing my design;

FIG. 2 is a top plan view;

FIG. 3 is a fragmentary side elevational view with the bit portion removed;

FIG. 4 is a top plan view thereof and;

FIG. 5 is a sectional view taken on line 5—5 of FIG. 4.
I claim:

The ornamental design for pipe cleaning implement, as shown.
